Specification of Letters Patent. Patented Oct. 31, 1911.

Application filed June 21, 1911. Serial No. 634,540.

To all whom it may concern:

Be it known that we, AUGUST ARENS and ERNEST L. TEICH, citizens of the United States, residing at New Britain, Hartford county, State of Connecticut, have invented certain new and useful Improvements in Locks, of which the following is a full, clear, and exact description.

Our invention relates to improvements in locks particularly adapted for hotel corridor doors.

The object thereof is to provide a lock which may be operated by a series of keys, including duplicate guest or change keys, a master key for unlocking all the doors on one floor, and a grand-master key adapted to unlock the doors on all floors under certain conditions. The series also includes a so-called emergency or proprietor's key, which is not only adapted to unlock all the doors on all floors, but also may so lock the door that it may be unlocked by any of the other keys, or so lock it that it may not be operated by any of the other keys.

A further object of the invention is to provide a thumb-turn and mechanism connected therewith by which the door may be locked from the inside in such manner that it may not be unlocked from the outside by any of the keys except one of the duplicate change keys or the emergency key.

A further object is to so construct the lock that the door may always be unlocked from the inside by the thumb-turn when locked from the outside by any of the keys.

For these several purposes the lock is provided with a key-operated pin tumbler or cylinder locking mechanism having a bolt-retracting cam arm and stop shoulders operating therewith, which in combination with the bolt mechanism proper and the thumb-turn mechanism, may serve to effect these objects.

With these objects in view, the invention consists in the construction and arrangement of parts, a preferred embodiment of which is illustrated in the accompanying drawings, in which—

Figure 1 is a side elevation of the lock with the cover plate removed to show the interior mechanism. Fig. 2 is a sectional view on the line 2—2 Fig. 1. Fig. 3 is a fragmentary view similar to Fig. 1, showing the bolt in locked position. Fig. 4 comprises a plan and side elevation of the bolt

tumbler. Fig. 5 comprises a side and edge view of a bell crank lever employed in the connections between the thumb-turn mechanism and the key-controlled pin tumbler mechanism. Fig. 6 comprises a side elevation and under side view of the locking bolt. Fig. 7 comprises a side elevation and edge view of a member of the connection between the thumb-turn and pin tumbler mechanisms. Fig. 8 comprises a side elevation and plan view of another member of the connection between the thumb-turn and pin tumbler mechanism. Fig. 9 comprises an end and side elevation of the thumb-turn roll-back. Figs. 10, 11 and 12 are sectional views of the pin tumbler mechanism, showing how the pin tumblers are positioned by the master, guest and emergency keys respectively. Figs. 13 to 17 inclusive, are diagrammatic views of the inner end of the pin tumbler mechanism showing the positions assumed by the parts in performing their several functions. Fig. 18 is a side view of the cam member of the pin tumbler mechanism. Fig. 19 is a side view of the actuating disk of the pin tumbler mechanism. Fig. 20 comprises side views of the master, guest and emergency keys respectively.

In the embodiment of our invention herein selected for illustration, 1 indicates a lock case having a face plate 2, locking bolt 3, and latch bolt 4 operable by a knob spindle connected with the roll-back 5.

6 indicates the body of a key-controlled pin tumbler mechanism having a key plug 7 (Fig. 10), a pin tumbler cylinder 8 for providing for a greater number of permutations of the lock in combination with the pin tumblers 9. At the inner end of the cylinder 8 is located a pair of concentrically mounted pin tumbler controlled cylinders 10 and 11, which are provided with stop shoulders adapted to coöperate with a stop shoulder on the bolt actuating cam member 12 in the manner hereinafter described.

13 indicates a cam actuating member, between which and the cam member may be interposed a friction ring 14 to hold the cam member in position when actuated by the key plug and cylinders 10 and 11. The dead bolt 3 has a tumbler 15 pivoted thereon at 16, said tumbler having a gate 17 coöperating with a fence 18 in the usual manner. The rear end of the tumbler has a lateral arm 19 extending into the path of the cam

arm 12 as the latter is rotated to project or retract the bolt. The lock is also provided with a thumb-turn roll-back 20, having the arms 21—21 adapted to engage the bolt to project and retract the same. The roll-back 20 is also provided with arms 22 engaging an extension 23 of the bolt tumbler 15, whereby said tumbler may be released from its fence 18 by means of the thumb-turn, 10 and the bolt may be thereafter retracted by said thumb-turn. It is desirable also that it be possible to retract the dead bolt from the outer side of the door by means of certain of the keys of the series when said bolt 15 has been projected by the thumb-turn from the inner side of the door. To this end we provide a sliding plate 24, having a vertical slot 25 (Fig. 8) at one end and a shoulder 26 at the opposite end. The slot 25 is engaged by a pin 27 carried by the bell crank lever 28, which lever is pivoted on the lock case at 29 and carries a second pin 30 engaged by a second sliding member 31 mounted by means of a slot 32 and a guide pin 33 25 on the lock case. To the upper end of this second sliding member 31 is pivoted an actuating arm 34, which, when the sliding member is raised to the position indicated in Fig. 3, is thrown by a pin 35 in the lock case into 30 the path of the key-controlled cam member 12.

Referring to the thumb-turn roll-back 20, this roll-back is provided also with arms 36 adapted to engage a cam surface 26 on the 35 slide 24. It will be seen also from an inspection of Fig. 9, that these roll-back arms 21, 22 and 36 are located in different parallel planes, one above the other, and that the sides of the roll-back slot 3^a of the lock- 40 ing bolt, the extension 23 of the tumbler 15 and the sliding plate 24 are located in correspondingly different planes, so that the arms 22 actuate the tumbler 15, the arms 21 actuate the dead bolt 3, and the arms 36 45 actuate or are actuated by the sliding plate 24. By this construction and the arrangement of the connections between the sliding plate 24 and the actuating arm 34 of the second slide 31, when said actuating arm 34 50 is engaged by the key-controlled cam member 12, as indicated in Fig. 3, further rotation of this cam member will cause the slide plate 24 to move forward simultaneously and with engagement of the roll-back arm 55 36 by the cam surface 26 of the slide 24, the roll-back will be rotated, thus retracting the bolt by means of its arms 21. Thus the dead bolt may be retracted from the outside through the pin tumbler mechanism and 60 the connections just described, when the bolt has been projected by the thumb-turn from the inside. It is desirable also that this operation of the bolt from the outside when projected from the inner side of the door 65 be confined to certain of the keys, such, for

example, as the duplicate change key and the emergency key. To this end, referring to Figs. 10 to 19 inclusive, the master key is adapted to rotate only the key plug 7 (see Fig. 10). The change key rotates the 70 key plug 7 and the inner cylinder 11 of the pair of cylinders 11 and 12, whereas the emergency key is adapted to rotate the key plug 7 and both of the cylinders 10 and 11. The cam member 12 is rotatably mounted on 75 the key plug, and is actuated by shoulders 14^a and 14^b on the actuating disk 14, which is fixed to the key plug. This cam member furthermore is provided with a stop shoulder or lug 12^a (Fig. 17) adapted to be 80 engaged by stop shoulders 10^a and 11^a on the inner ends of the cylinders 10 and 11 respectively (see Fig. 13).

Fig. 13 illustrates the normal position of the key plug, the several pin tumbler cylinders, the actuating disk and the cam member. From this it will be evident that all of the keys may project the dead bolt by rotation of the cam member 12 in a clockwise direction (as viewed in Fig. 13) until the cam member assumes the position indicated in Fig. 14, since neither of the stop shoulders 10^a or 11^a hinder rotation of the cam member in this direction. When, however, the dead bolt has been projected by the thumb-turn 95 from the inner side of the door, it is evident from an inspection of Figs. 1 and 3, that said bolt can only be retracted by rotation of the cam member in a direction counterclockwise from the position indicated in Fig. 17. 100 Since the master key only rotates the key plug, it is obvious that this counterclockwise rotation of said key will be prevented by the stop shoulder 11^a on the cylinder 11, as shown in Fig. 11. Again, since the change 105 key rotates only the key plug and inner cylinder 11, this key can only rotate the cam member counterclockwise from normal position until the lug 12^a is stopped by the stop shoulder 10^a of the outer cylinder 10. Such 110 rotation, however, is insufficient to retract the dead bolt, as will be seen from an inspection of Figs. 1 and 3. It is therefore necessary to provide means by which the cam member may retract the dead bolt during its short 115 travel from normal position shown in Fig. 13, to the position shown in Fig. 16. Such mechanism comprises the actuating arm 34, slide 31, bell crank lever 28, slide 24 and roll-back 20, with its several arms, for when 120 the cam member is rotated counterclockwise from normal position in Fig. 13, as it may be by the change and emergency keys (but not by the master or grand-master keys), said cam member engages the arm 34, and, through the series of members just mentioned, causes the cam surface 26 of the slide 24, by its engagement with one of the arms 36 of the roll-back, to partially rotate 125 said roll-back, so that the arm 22 will first 130

release the tumbler 15 from the fence 18, and thereafter a lug 24^a on the rear of the slide 24 continues the rotation of the roll-back 20 by engagement with one of its arms 21 and causes the other of said arms 21 to retract the dead bolt. The rotation of the roll-back 20 to normal position is completed by pressure of the extension 23 of the tumbler 15 on the broad side of said roll-back. 5 Hence, retraction of the dead bolt from the outer side of the door when projected by the thumb-turn from the inside is restricted to the change and emergency keys. 10

The rear wall of the slot 3^a, which is engaged by the arms 21 of the roll-back 20, is formed by a detent 3^b pivoted at 3^c, whereby the arms 21 of said roll-back may trip and clear said detent 3^b in projecting the dead bolt, and engage the front wall of said detent to retract the dead bolt, when the dead bolt has been projected by the thumb-turn or projected from the outside while the occupant is in the room. 20

It is sometimes desirable that access to the room be confined to the holder of the emergency key or proprietor. For this purpose the dead bolt may be projected by rotation of the cam member 12 from normal position in Fig. 13, clockwise for a complete revolution, since the emergency key rotates both of the cylinders 10 and 11, as well as the key plug 7, whereby the lug 12^a on the cam member 12 is not blocked by either of the shoulders 10^a or 11^a in such rotation, but all of 30 these parts travel bodily together. The actuating arm 34 of the slide 31 is capable of turning upwardly to a certain extent to permit the free passage of the cam member in such rotation, when said arm is in the position indicated in Fig. 1, thus leaving said arm 34 out of the path of the cam arm, in which case the bolt can only be retracted by counterclockwise rotation of the cam member 12 by the emergency key. 40

When the bolt is so projected by a complete rotation of the emergency key and the pin cylinders, key plug and cam arm left in normal position, as indicated in Fig. 17, it is obvious that the bolt cannot be retracted 50 by any of the other keys of the series, for the reason that in the case of the master and grand-master keys, the cam member 12 cannot rotate counterclockwise, Fig. 17 (the direction necessary to retract the bolt), owing 55 to the engagement of its stop shoulder 12^a with the stop shoulder 11^a. Likewise, the bolt cannot be retracted by the guest key, for the reason, first, that the arm 34 is out of the path of the cam arm, and second, the stop lug 12^a will be blocked by the stop shoulder 10^a of the pin cylinder 10 before the lever 60 can be rotated far enough to retract the dead bolt. Thus the emergency or proprietor's key may block the lock against the operation of any of the other keys of the series. 65

While we have herein described a particular embodiment of our invention, it is to be understood that the same may be altered in detail and relative arrangement of parts without departing from the spirit and scope 70 of the appended claims.

What we claim is:

1. In a lock, the combination with a dead bolt, of a pin tumbler mechanism for operating the same from the outer side, a thumb turn for operating the same from the inner side, a series of keys for operating said tumbler mechanism, including duplicate change keys and an emergency key, and means in said pin tumbler mechanism for 80 confining retraction of said dead bolt to said change and emergency keys when projected by said thumb-turn. 75

2. In a lock, the combination with a dead bolt, of a pin tumbler mechanism for operating the bolt from the outer side, a thumb-turn for operating said bolt from the inner side, a series of keys including duplicate change keys and an emergency key, a connection between said pin tumbler mechanism and said roll-back whereby said roll-back may be operated by said pin tumbler mechanism to retract the dead bolt when projected by the thumb-turn, and means in 90 said pin tumbler mechanism to confine such 95 retraction of the dead bolt to said change and emergency keys. 85

3. In a lock, the combination with a dead bolt, of a pin tumbler mechanism including a plurality of pin tumbler cylinders and a 100 cam arm, an actuating disk for said arm, a series of keys for said lock including duplicate change keys and an emergency key, a thumb-turn roll-back adapted to operate said bolt from the inner side of the door, operative connections between said pin tumbler mechanism and said roll-back whereby 105 said dead bolt may be retracted by said pin tumbler mechanism by the change and emergency keys, and stop shoulders on said cam 110 arm and said pin tumbler cylinders to prevent retraction of the dead bolt by any except the change and emergency keys when the bolt has been projected by the thumb-turn. 115

4. In a lock, the combination with a dead bolt, of a tumbler and fence therefor, a key-controlled pin tumbler mechanism having a cam arm adapted to release said bolt tumbler and to project and retract the dead bolt 120 from the outer side of the door, a thumb-turn and roll-back adapted to release said bolt tumbler and to project and retract the dead bolt from the inner side of the door, and a connection between said pin tumbler mechanism and said roll-back whereby said bolt tumbler may be released and the bolt retracted by the operation of said pin tumbler mechanism on said roll-back through 125 said connection. 130

5. In a lock, the combination with a dead bolt, of a key-controlled pin tumbler mechanism comprising a key plug, a bolt actuated cam arm rotatably mounted thereon, an actuating disk fixed to said plug, a plurality of pin tumbler cylinders mounted concentrically on said key plug, stop shoulders on said cam member and said pin tumbler cylinders respectively, a series of keys including change keys and an emergency key adapted to operate said pin tumbler mechanism to project and retract the dead bolt, said pin tumblers and said stop shoulders being so constructed and arranged to limit the extent of rotation of said cam member by all of said keys except said emergency key where-with said emergency key may project the dead bolt and position the pin tumbler mechanism so that said dead bolt cannot be retracted 20 by any of the other keys of the series.

6. In a lock, the combination with a dead bolt, of a key-controlled pin tumbler mechanism, including a bolt actuating cam arm, a series of keys adapted to operate the same including change keys and an emergency key, a thumb-turn and roll-back adapted to operate said bolt from the inner side of the door, a member having a part adapted to extend into the path of said cam arm, a second member adapted to actuate said roll-back and connected with said first member where-by said roll-back may be operated to retract the dead bolt by said cam member, and means in said pin tumbler mechanism for restricting such operation to the change and emergency keys.

7. In a lock, the combination with a dead bolt, of a key-controlled pin tumbler mechanism including a bolt actuating cam arm

adapted to project and retract said bolt, a 40 thumb-turn and roll-back operable from the inner side, a bolt tumbler constructed and arranged to be released both by said cam arm and said roll-back, connections between said cam arm and said roll-back whereby the 45 latter may be operated by the former to release said bolt tumbler and project the dead bolt, and means in said pin tumbler mechanism to confine such operation to certain of the keys of the series. 50

8. In a lock, the combination with a dead bolt, of a key-controlled pin tumbler mechanism comprising a cam arm for projecting and retracting the dead bolt from the outer side of the door, a thumb-turn and roll-back 55 for projecting and retracting the dead bolt from the inner side of the door, a bolt tumbler mounted on said bolt, said roll-back having an arm to release said tumbler and having an arm to project and retract the 60 dead bolt, a connection between said pin tumbler mechanism and said roll-back having a portion adapted to lie in the path of said cam member and having a portion 65 adapted to engage said third arm of the roll-back to actuate said roll-back to retract the dead bolt when said connection is operated by said cam arm, a series of keys adapted to operate said pin tumbler mechanism including change keys and an emergency 70 key, and means to confine actuation of said roll-back from said pin tumbler mechanism to said change and emergency keys.
